UNITED STATES PATENT OFFICE.

GEORGE A. WOODMAN, OF CHICAGO, ILLINOIS, ASSIGNOR TO KIRBY EQUIPMENT COMPANY,
OF CHICAGO, ILLINOIS, A CORPORATION OF ILLINOIS.

JOURNAL-BOX.

No. 914,326.

Specification of Letters Patent.

Patented March 2, 1909.

Application filed November 29, 1907. Serial No. 404,364.

To all whom it may concern:

Be it known that I, GEORGE A. WOODMAN, a citizen of the United States, residing at Chicago, in the county of Cook and State of Illinois, have invented new and useful Improvements in Journal-Boxes, of which the following is a specification.

This invention relates to improvements in journal boxes and more particularly to that 10 type of journal boxes for car axles having a lid which is made to swing edgewise.

The object of the invention is to provide for holding the edgewise swinging lid of a journal box securely in its open and closed 15 positions and to close the lid automatically and tightly when it is released from open position.

A further object of the invention is to provide a journal box with an edgewise swinging lid which is normally held tightly closed 20 against the box and is hinged thereto in a novel manner whereby the lid is caused to move outwardly away from the box as the lid is opened and inwardly against the box as 25 it is closed.

In the accompanying drawings Figure 1 is a front elevation of a journal box embodying my invention and showing the hinge at the right side of the box. Fig. 2 is a similar 30 view with the lid removed. Fig. 3 is a view of the inner face of the lid upside down. Fig. 4 is a front elevation of a journal box showing the hinge at the top of the box. Fig. 5 is a view similar to Fig. 1 showing the lid in open 35 position. Fig. 6 is a detail view showing the cams on the lid. Fig. 7 is a similar view showing the cams on the box. Fig. 8 is a sectional view on the line 8—8 of Fig. 1. Fig. 9 is a detail sectional view showing the 40 position of the pintle reversed.

Referring to the drawings, 9 designates a journal box having an opening 10 generally rectangular in shape and surrounded by flat faced walls 11. The invention has relation 45 more particularly to the lid and the manner of hinging the lid to the box and therefore it can be embodied in boxes of different constructions. For this reason I have shown the box in a more or less conventional form. A lug 12 projects outward from the box adjacent to one wall of the opening 10 and this lug is provided in its front face with two cam recesses 13 and 14 radially disposed on opposite sides of the pintle opening 15. In the 50 construction shown in Fig. 2, in which the

hinge is located at one side of the box, the high point 13' of the cam 13 is located above the pintle opening and the high point 14' of the cam 14 is located below the pintle opening and these high points are made wide and 60 flat for a purpose hereafter described. Between the high point 14' of cam 14 and the low point 13'' of cam 13 there is a flat section 16 and between the high point 13' of cam 13 and the low point 14'' of cam 14 there is a 65 similar flat section 16'.

A lid 17 (Fig. 3) is made with a flat inner face to fit tightly against the flat faced walls 11 on the box and I may provide a flange 18 at the top of the lid on the inner face thereof 70 to project over the wall at the top of the box. The lid is provided at one edge with a lug 19 corresponding in location and general form to the lug 12 on the box and having a pintle opening 15'. This lug 19 is provided 75 on its rear face with projecting cams and flat sections between the cams complementary to those on the box lug. The cam 20 is located at the left and the cam 21 at the right of the pintle opening and the high 80 points 20' and 21' of these cams are made wide to correspond with the high points 13' and 14' of the cam recesses in the box. There are also flat sections 22 and 22' between and separating the cams 20 and 21 85 corresponding to the flat sections 16 and 16' on the box lug. Reference has been made to the particular location and arrangement of these cams to enable the invention to be more readily understood and read on the 90 drawings, but the invention does not depend upon this particular arrangement and it is important to the extent only that by the engagement of the shoulders 20'' and 21'' on the high points of the lid cams with the 95 shoulders 13''' and 14''' on the high points of the cam recesses in the box a limit is provided to the closing swing of the lid so that the movement of the lid to closed position will stop with the lid properly centered over 100 the opening in the box. A stop projection 23 on the lid lug may be provided to engage the box in or about the manner shown in Fig. 5 to limit the opening swing of the lid.

A pintle 24 extends transversely through the opening 15' in the lid lug and the opening 15 in the box lug and is provided with a head 24' which is preferably countersunk in the lid lug. (Fig. 8.) The end 24'' of this pintle is threaded and projects some dis- 105 110

tance beyond the box lug 12. A spring 25 is arranged on the pintle with one end bearing against the box lug and the other end inclosed in a cup washer 26. This spring is held in place on the pintle and at proper tension by a nut 27 on the threaded end of the pintle which bears against the washer 26 and by a cotter pin 28. The construction must be such that the lid shall be permitted 10 an outward movement in a direction lengthwise of the pintle sufficient to permit the high points of the lid cams to travel up on the high points of cam recesses in the box, and the spring is therefore adjusted to proper 15 tension for this purpose and to hold the lid securely in position when closed and when open. The lid is provided at its edge opposite the lug with a hook 29 or some other projection or device which can be engaged 20 to open the lid.

While in general practice the hinge will probably be located almost universally at the right side of the box it will be apparent that without departing from my invention 25 in any respects the hinge can be located at the left side, at the top or at the bottom of the box and the cams can be easily located in proper position wherever the lugs are arranged to permit the lid to be opened in 30 the manner described and as far as may be desired.

When the lid is closed the high points of the cams will engage the flat sections and the spring holds the lid in this position tightly 35 against the flat faced walls surrounding the opening in the box and forming a close and dirt proof closure. As the lid is swung edge-wise to open position the cams on the lid travel up on the cam recesses in the box 40 until the high points of the cams on the lid engage the high points of the cam recesses in the box. As these high points have some

width and are flat on their faces the lid will be held by the spring in open position until it is swung backward and the cams on the lid begin to travel down the cam recesses in the box. After the return movement is started it proceeds very quickly because the spring makes the cams on the lid travel quickly down the cam recesses in the box 50 to carry the lid into closed position. The outward movement of the lid, as it is opened, and the inward movement of the lid, as it is closed, occur during the edgewise movement of the lid.

I prefer to arrange the pintle with the head at the front of the lid as shown in Fig. 8 but this arrangement may be reversed, as shown in Fig. 9, and the same result produced.

While I have shown the pintle secured in 60 the lugs and the spring held in place by a nut, a washer and a cotter pin on the pintle, it will be apparent that any other fastening means suitable for the purpose may be employed without departing from my invention.

What I claim and desire to secure by Letters Patent is:

The combination of a journal box for car axles having an opening therein, a lid hinged to said box and movable edgewise over said opening, said box and lid having lugs thereon located opposite each other, there being cam recesses in the front face of the box lug separated from each other and projecting cams on the rear face of the lid lug separated from each other and adapted to travel in the cam recesses in the box lug, a pintle arranged in said lugs to hinge the lid to the box, and a spring on said pintle for holding the cam faces of said lugs in engagement.

GEORGE A. WOODMAN.
